US0D1015934S

(12) **United States Design Patent** (10) Patent No.: **US D1,015,934 S**
(45) Date of Patent: ** Feb. 27, 2024

(54) **CLIP FOR A STRAP**

(71) Applicant: **Under Armour, Inc.**, Baltimore, MD (US)

(72) Inventors: **Derek Campbell**, Baltimore, MD (US); **Bradley Johnson**, Salt Lake City, UT (US); **Seden Craig**, Baltimore, MD (US)

(73) Assignee: **Under Armour, Inc.**, Baltimore, MD (US)

(**) Term: **15 Years**

(21) Appl. No.: **29/820,896**

(22) Filed: **Dec. 24, 2021**

(51) LOC (14) Cl. **02-07**

(52) U.S. Cl.

USPC **D11/218**

(58) **Field of Classification Search**

(57) **CLAIM**

The ornamental design for a clip for a strap, as shown and described.

DESCRIPTION

FIG. 1 is a front view in perspective of a clip for a strap, showing our new design;

FIG. 2 is a rear view in perspective thereof;

FIG. 3 is a front view thereof; and

FIG. 4 is a rear view thereof;

FIG. 5 is a first side view thereof;

FIG. 6 is a second side view thereof;

FIG. 7 is a bottom view thereof; and

FIG. 8 is a top view thereof;

FIG. 9 is a rear view in perspective of a backpack with a clip showing our new design;

FIG. 10 is a front view thereof;

FIG. 11 is a rear view thereof;

FIG. 12 is a partial rear view thereof showing portions of straps with clips for the backpack;

FIG. 13 is a first side view thereof;

FIG. 14 is a second side view thereof;

FIG. 15 is a top view thereof; and,

FIG. 16 is a bottom view thereof.

The broken lines in FIGS. 9-16 depict environmental subject matter that forms no part of the claimed design.

1 Claim, 13 Drawing Sheets
